SAFETY DEVICE FOR TYPOGRAPHICAL MACHINES

Filed Aug. 31, 1929

UNITED STATES PATENT OFFICE

ARTHUR G. SPERRY, OF HOLLIS, NEW YORK, ASSIGNOR TO INTERTYPE CORPORATION,
OF BROOKLYN, NEW YORK, A CORPORATION OF NEW YORK

SAFETY DEVICE FOR TYPOGRAPHICAL MACHINES

Application filed August 31, 1929. Serial No. 339,826.

This invention relates to typographical machines of the general class disclosed in Letters Patent of the United States, No. 436,532, granted Sept. 16, 1890 to O. Mergenthaler, wherein circulating matrices are released from a magazine under control of a keyboard and composed in a line, the line then transferred into a vertically movable

“first elevator” or matrix-supporting member which presents it to the mold, whereupon the mold is filled with molten metal to cast a type-bearing slug against the matrices, and the matrices thereafter returned through a distributing mechanism to the magazine.

In the operation of machines of this character, the composed line of matrices is presented to the mold in predetermined relationship with respect to certain alignment means common to the associated parts which retain the matrix line for casting, and if such relationship is impaired, through inadvertence in the setting of the machine, or otherwise, then the mold would collide with the matrix supporting member and this would damage the machine and an opening would result which would allow molten metal when delivered from the pot into the mold against the line of matrices to squirt.

An object of this invention is to provide means in typographical machines of the class described for automatically stopping the operation of the machine when a composed line of matrices is improperly aligned, or, through some obstruction between the matrix retaining member and the mold, the parts are not brought together normally, thereby safeguarding the machine from damage and insuring safety to the operator from the effects of a metal squirt.

More particularly, the object of the invention is to provide improved means for carrying out the invention described in U. S. Letters Patent to S. E. Sperry, No. 1,674,415 granted June 19, 1928 in which the principal object was the same as stated above but in which the means for carrying out said object has been found to involve certain difficulties owing to the limited space available in which to accommodate the various parts. The present invention greatly simplifies the means

necessary to insure the desired safety as well as to greatly reduce the space required for the operating parts and at the same time secure a more positive action.

With the foregoing and other objects in view, the invention consists in certain improvements and combinations and arrangements of parts as will be hereinafter described, it being understood that the invention is not limited to the precise embodiment herein disclosed since equivalent constructions are contemplated and such will be included within the scope of the appended claims.

In the accompanying drawings:

Fig. 1 is a fragmentary view partly in section taken vertically through the casting mechanism of a line casting machine, showing the invention applied thereto, the parts being shown in actuated position;

Fig. 2 is a top plan view of a portion of the structure shown in Fig. 1;

Fig. 3 is a side elevation of certain of the parts illustrated in Fig. 1 but showing these parts in normal position; and

Fig. 4 is a perspective view of a portion of the stop mechanism of the machine, showing the improved safety means applied thereto.

Similar parts are designated by the same reference characters in all of the figures.

The safety device of the present invention is applicable generally to typographical machines of the class referred to, and since the construction and mode of operation of such machines are well known and the S. E. Sperry U. S. Letters Patent above referred to clearly shows a generally similar safety device applied to the cooperating parts which are commonly used in such machines, the description herein is confined to the particular parts of the machine affected by this invention.

It is well understood in the art that in the operation of machines of the class hereinbefore referred to, the matrices are assembled in a line and the line carried before the mold while held between a pair of jaws 1 which are fixed on an elevator, and it is common practice, as disclosed in U. S. Letters Patent No. 1,439,586 granted Dec. 19, 1922 to M. L. Van Keuren to provide this elevator with

an adjusting screw 2, and to bring the jaws down to any one of a plurality of levels with respect to the mold in accordance with the setting of a bar 3 provided with studs 4 of different heights upon which the adjusting screw 2 banks, the bar 3 being carried by a fixed portion of the machine and being slideable therein to bring one or another of these studs 4 into position to be engaged by the screw 2 and thereby arrest the downward movement of the jaws at different levels, according to the stud engaged by the adjusting screw 2.

If the slideable aligning bar 3 should be inadvertently set to position a wrong height stud under the set screw, a condition would exist as clearly shown in Fig. 1 wherein the bottom lugs of matrices would not align with the grooves 5 of the mold which is carried on the usual mold wheel 6, and as the mold wheel is pushed forward, to close the mold against the line of matrices preparatory to casting a slug, as is the usual method of operation, the resulting obstruction would cause damage to the matrix lugs and to the mold, as well as the matrix supporting jaws.

The safety means shown in my prior patent hereinbefore referred to prevents such damage by providing the lever which ordinarily acts as a direct and rigid means for driving the usual mold wheel and slide forward, with supplemental yieldable lever means which prevent the mold slide and wheel from being driven forward against any obstruction with undue force, but the application of said yieldable lever means in the manner shown in said patent obviously requires considerable space and the supporting mechanism of the machine adjacent thereto will not always permit making such levers of sufficient size to insure substantial strength. Moreover, such yieldable lever means is so extremely sensitive that it is objectionable because it comes into action upon the break-away of the metal pot from the mold after the casting of a slug. For instance, when the metal pot mouthpiece or the type metal becomes somewhat chilled, it is well known that the break-away of the metal pot from the mold requires the exertion of considerable force because the chilled metal in the fine holes of the pot mouthpiece solidifies with that in the back of the slug in the mold. The metal pot however is compelled to move back by its own controlling cam and roller so that the strong back pull to break the mouthpiece away from the slug also tends to pull the slug back and this in turn transmits the back pull to the entire mold wheel and slide whereupon, the sensitive yieldable levers are acted upon in some cases to such an extent as to cause them to work in a reverse direction and to inadvertently throw out the clutch, thereby stopping the machine.

The present invention aims to improve the

action of such a safety device by constructing it so that it will only come into action upon the forward or advance movement of the mold slide whenever an obstruction to such movement occurs. In reality, the present invention provides a construction which is a reversal of that shown in my said prior patent in the sense that the yieldable overmotion instead of being applied to the usual mold cam lever to compensate for interrupted movement of the mold slide as in my said prior patent, is, in the present instance, applied to the mold slide. The improved construction also permits the device to be applied in a position in the machine where more space is available and without obstructing or requiring the alteration of other supporting parts of the machine.

Referring to the drawings showing the improved construction, Fig. 1 shows the usual mold slide lever 7 suspended by the pivot 7^a from the usual hand lever 8^a of the pump bracket 9^a fixed to the main frame of the machine. The lower end of the lever 7 carries two rollers 8 and 9, the roller 8 engaging in a curved recess 10 formed in the back end of the usual mold slide 11. The mold wheel 6 is carried on an arm 12 which is also a part of the mold slide and the slide itself is formed with beveled surfaces at the top and bottom to fit into ways in the main column 13 of the machine. The lever 7, by engagement of its roller 8 with the mold slide 11, transmits a forward movement to the mold slide at the proper time, the motion being controlled by engagement of the roller 9 also on lever 7 with the surface 14 of a cam groove in the usual mold cam and gear wheel 15 of the machine as shown in Fig. 3.

The usual vertical starting lever shaft 16 is commonly provided with two levers 17 and 18 suitably pivoted on pivot pins 17^a and 18^a and in slots in the shaft which is mounted at top and bottom in bearing lugs 19 carried on the main frame 13. In the normal operation of machines of this class which do not have a mold slide safety device, the so called vertical lever 17 and its actuating lever 18 cooperatively act through adjusting screw 19^a and the starting lever of the machine, not shown here but the operation of which is well understood, to throw the usual clutch lever 20 in such a manner that its forked arm working against the collar 21 of the clutch shaft 22 operates the clutch mechanism of the machine, such as that shown in United States Patent No. 661,386 granted Nov. 6, 1900 to J. R. Rogers, to throw the driving power off or on as required, it being common and well understood that the clutch mechanism is usually driven by an electric motor or other power means and that the entire machine, including the cam 15, is driven from and controlled by said clutch mechanism.

To carry out the present invention, the

5 mold slide 11 is provided with a spring 23 and plunger 24 carried in a longitudinal recess drilled into the mold slide casting. The recess 10 in the rear end of the mold slide is made somewhat larger than the usual recess 10 in the rear end of the mold slide 10 in order to give the roller 8 freedom of movement back and forth longitudinally of the mold slide, and the plunger 24 normally protrudes rearwardly into the recess under the 15 action of the spring 23 so that its nose rests against the roller 8 and yieldingly holds the lever 7 swung back with the roller 8 occupying the back position in the recess 10 as shown in Fig. 3, the spring 23 being of sufficient 20 strength to overcome the weight of the lever 7.

Excess rearward movement of the plunger 24 when the roller is lifted out of the recess 10 by operation of the hand lever 8^a is prevented by a pin 33 which is fixed in the mold slide 11 and projects into a slot 34 of suitable 25 length and extending longitudinally in the plunger. The upper so called vertical lever 18 pivoted in the vertical shaft 16 according to the present invention, is provided with a 30 laterally extending ledge 25 which may be an integral part thereof and this extended portion is fitted with a slideable block 26 which carries an angular plate member 27 secured thereto by screws 28, the member 27 having a laterally offset arm 29 and an adjusting screw 30 therein for imparting sliding motion to the block 26 through contact of the screw 30 with the outer face of the rear end of the recessed portion of the mold slide. The 35 slideable block and plate member 26, 27 is yieldingly urged toward a forward position by a tension spring 31, one end of which is fastened to a hook 32 in the top of the plate member 27 and the other end to an angular hook 32^a fastened in the web portion of the lever 18 which reinforces and supports the ledge 25 from below. Sliding movement of the block 26 and its plate 27 is limited by providing a groove 39 in the side of the block 40 into which a screw 40 fastened in the ledge 25 of lever 18 will engage and serve as a stop against the shoulders at the ends of the groove 39.

In the normal operation of the machine, the 45 lever 7 will swing forwardly about its pivot 7^a as the cam surface 14, which is driven by power supplied to the clutch shaft 22 by an electric motor or other power means, works against the roller 9, while the roller 8 resting in the recess 10 of the mold slide will impart, for instance, forward motion thereto, the roller 8 pushing against plunger 24, but plunger 24 will be held back by the powerful 50 spring 23 so that the mold slide will move forward and cause the mold on the mold wheel at the forward end of the slide to advance and lock up against the line of matrices presented thereto. Fig. 3 shows the plunger 24 in normal position resting against the roller 8.

55 In the event of a misalignment of the

matrix lugs or the matrix retaining members with the mold on the mold wheel, due to an inadvertent setting of the matrix aligning bar 3, the mold cam lever 7 will be forced to swing about its fulcrum 7^a in the usual manner and the lower end of the lever will carry roller 8 forward with it. The inadvertent obstruction, however, will prevent the mold slide together with the mold wheel from advancing forwardly and the roller 8 will 60 then act against the nose of plunger 24 and will move the latter forwardly and compress the spring 23 so that the obstruction in front of the mold will only receive a limited pressure against it without doing any harm to the parts involved in the obstruction in front of the mold.

If the machine were allowed to continue to operate with only this provision to eliminate damage in front of the mold, the presence of such obstruction may not be at once recognized by the operator and might still result in damage which can be avoided. To this end, the usual delivery and elevator transfer cam of the machine which already 65 carries automatic stopping pawls, of no concern with the present invention and therefore, not shown, is arranged to carry a small block which acts as an additional stopping pawl for the machine. A fragmentary part of the cam just mentioned is here shown in Figs 1 and 2 and designated 35, and the block fastened to the side thereof is designated 36. As already explained, the block 26 with its plate member 27 secured thereto is held in a forward position under the tension of spring 31, the adjusting screw 30 in the plate 27 resting against the rear exterior surface of the recessed portion of the mold slide and thus determining 70 the forward position of the block 26. If the mold slide moves forwardly normally or without any obstruction in its path, the block 26 and plate member 27 along with the adjusting screw 30 will advance with it and the block 26 will thus be carried out of the path of the block 36, but if an obstruction occurs in the path of the mold slide, as in Fig. 1, the block 26 with plate 27 will also 75 be stopped from moving forward so that a portion of the block 26 will project rearwardly into the path of the block 36 on cam 35. This obstruction to rotation of cam 35 will cause the upper vertical lever 18, which carries the block 26, to pivot about its pivot pin 18^a in the vertical shaft 16, and this in turn will cause the lower end of the lever carrying the banking screw 19^a to move forward against the upper end of the lower vertical lever 17. The lever 17 will then 80 swing about its pivot pin 17^a also in the vertical shaft 16, and the lower end of this lever will then operate against the usual machine clutch lever 20, the forked end of which will force the collar 21 to move out- 85

ward and operate the main driving clutch to throw it in off position and thereby stop the machine so that the casting mechanism will not operate and hence there will be no metal squirt through the opening left between the improperly positioned matrix line and mold.

As is usual in machines of this character, the mold disc 11 and mold wheel 6 may be moved forwardly independently of its operating lever 7 or other associated mechanism by depressing the handle of the hand lever 7^a which will cause the lever 7 to rise and to lift its roller 8 out of engagement with the recess 10 at the rear end of the mold slide, thus disconnecting the mold slide from its driving means. The present invention does not disturb or interfere with this detachable relationship between the mold slide and its operating lever.

I claim as my invention:—

1. A typographical machine including means for supporting a line of matrices, a mold carrier and mold movable to present the mold to the line of matrices, power-driven means for moving the mold carrier, and means on the mold carrier for yieldingly transmitting motion thereto from said power-driven means.

2. A typographical machine including means for supporting a line of matrices, a mold carrier and mold movable to bring the mold into casting position against the matrices, a power-driven lever for moving the mold carrier into casting position, and means on the mold carrier and engaged by a part of said lever for yieldingly transmitting motion from said lever to the mold carrier to move the latter toward casting position.

3. A typographical machine including means for supporting a line of matrices, a mold slide and mold movable to bring the mold into casting position against the matrices, a power-driven member for moving the mold slide, and a spring pressed plunger on the mold slide and movable relatively to it in the direction of movement of said slide and engaged by a part of said member for yieldingly transmitting motion from said member to the mold slide to move the latter toward casting position.

4. A typographical machine including means for supporting a line of matrices, a mold slide and mold movable to bring the mold into casting position against the matrices, said slide having a recess therein, a power-driven lever having a part removably engageable in said recess in the mold slide, and means extending into said recess to engage the part of said lever therein and yieldably transmit motion from said lever to the mold slide to move the mold into casting position.

5. In a typographical machine including a clutch controlling its operation, clutch operating means, means for supporting a line of

matrices, a mold slide and mold movable to bring the mold into casting position against the matrices, and power driven means for moving the mold slide, means engaging and movable in unison with the mold slide for actuating the clutch operating means to stop the operation of the machine when the normal movement of the mold slide into casting position is interrupted. 70

6. In a typographical machine including a clutch controlling its operation, clutch operating means, means for supporting a line of matrices, a mold slide and mold movable to bring the mold into casting position against the matrices, and power-driven means for moving the mold slide, means for yieldingly transmitting motion from said power-driven means to the mold slide to move it toward casting position, and means including a part engaging the mold slide for actuating the clutch operating means to stop the operation of the machine when the normal movement of the mold slide into casting position is interrupted. 75

7. In a typographical machine including a clutch controlling its operation, clutch operating means, means for supporting a line of matrices, a mold carrier and mold movable to bring the mold into casting position against the matrices, and power-driven means for moving the mold carrier, means for yieldingly transmitting motion from said power-driven means to the mold carrier to move the mold toward casting position, and means including a part engaging the mold carrier and governed by the extent of actual movement of the mold carrier toward casting position for actuating the clutch operating means to stop the operation of the machine when the normal movement of the mold carrier is interrupted. 90

8. In a typographical machine including a clutch controlling its operation, a clutch operating shaft having clutch operating means thereon, a power-driven stopping member cooperative with said clutch operating means, and a mold slide and mold movable to bring the mold into casting position, a controlling member movably mounted on said clutch operating means and engaging and moving in accordance with the movement of the mold slide toward casting position, said controlling member being in the path of said stopping member when the normal movement of the mold slide into casting position is interrupted and causing actuation of said clutch operating means to stop the operation of the machine. 100

9. In a typographical machine including a clutch controlling its operation, a clutch operating lever, a cooperative stopping member for actuating it, and a mold slide and mold movable to carry the mold into casting position, a controlling member mounted on said clutch operating member to occupy pos- 110

120

130

tions in and out of the path of said stopping member, said controlling member having a part engaging the mold slide and governing the position of said controlling member relatively to said stopping member.

5 10. In a typographical machine including a clutch controlling its operation, a clutch operating lever, a stopping member for actuating said lever, and a mold slide and
10 mold movable into casting position, a clutch controlling slide mounted on the clutch operating lever to move into and out of the path of said stopping member, said controlling slide having a part which engages the mold
15 slide and causes the controlling slide to move in accordance with the movements of the mold slide.

In testimony whereof I have hereunto set my hand.
